UNITED STATES PATENT OFFICE.

ELMER DONADON AND MICHAEL M. MATHES, OF ST. LOUIS, MISSOURI, ASSIGNORS TO AMERICAN CAR AND FOUNDRY COMPANY, OF ST. LOUIS, MISSOURI, A CORPORATION OF NEW JERSEY.

FOLDING STAKE-POCKET.

1,123,181.

Specification of Letters Patent. Patented Dec. 29, 1914.

Application filed July 27, 1914. Serial No. 853,332.

To all whom it may concern:

Be it known that we, ELMER DONADON and MICHAEL M. MATHES, citizens of the United States, residing in the city of St. Louis, State of Missouri, have invented a certain new and useful Improvement in Folding Stake-Pockets, of which the following is a full, clear, and exact description, such as will enable others skilled in the art 10 to which it appertains to make and use the same, reference being had to the accompanying drawings, forming part of this specification.

This invention relates to folding stake pockets for use on railway cars, the essential 15 feature of the device being that it may be swung to a vertical position where it is out of the way of possible injury or interference with other objects, and to a horizontal position, in which it may be secured to hold a stake.

In the drawings, Figure 1 is a front view 20 of the device showing the stake engaging portion in its horizontal operative position. Fig. 2 shows the stake engaging portion in its vertical or inoperative position. Fig. 3 is a side view looking at the left side of Fig. 1. Fig. 4 is a side view looking at the right side of Fig. 1.

The object of our invention is to provide 25 a folding stake pocket which may be swung into either horizontal or vertical position, and secured in such position by a lateral shifting of the swinging member relative to the attaching members.

It is a further object of our invention to provide a stake pocket of this description which is very economical, strong and easy to operate.

With the foregoing objects in view, it will 30 be understood, by reference to the drawings, that 1 represents suitable brackets which may be attached to the side of the car to form supports for the swinging member 2. These brackets 1, best seen in Figs. 3 and 4, are bent to form angular seats 5 in which the lateral portions 6 of the swinging member 2 operate.

The swinging member 2 has its medial 35 portion bent to form a loop which is adapted to engage a stake to hold it in position. The spacing of the brackets 1, relative to the width of the stake engaging portion, is such as to permit a lateral shifting of the swinging member in the brackets, the lateral por-

tions 6 of the swinging member being of sufficient extent to remain in engagement with the brackets upon such shifting movement. Except for one extremity 6^a of one of the lateral members 6, such lateral members are round so as to have rotating engagement with the brackets 1. Such extremity 6^a is angular and is so formed as to have non-rotating engagement with its coöperating bracket 1 when shifted into engagement therewith by the lateral shifting of the swinging member.

It is believed that the operation of the device is obvious from the foregoing description, from which it will be understood 40 that when the swinging member is in its inoperative or vertical position illustrated in Fig. 2, it may be swung to horizontal position, and then shifted laterally to bring the angular extremity 6^a into engagement with the seat of the coöperating bracket, which engagement, as above described, holds the swinging member against rotation relative to the brackets. When in its horizontal position, the swinging member may be simply shifted to its vertical position by moving it laterally to disengage the angular portion 6^a from the bracket, whereupon it will assume a vertical position by force of gravity. The swinging member may be locked in its 45 vertical position by again shifting it so that the extremity 6^a will be engaged in the seat of the coöperating bracket.

We are aware that changes and modifications may be made in the device without departing from the scope of what we claim to be our invention, and therefore we do not intend that the invention be limited to the specific form shown.

We claim—

1. A folding stake pocket having bracket members adapted for attachment to a car, a swinging member having a portion adapted to engage a stake and axial lateral portions supported in said brackets, said lateral portions having parts thereof adapted for rotative coöperation with said brackets and a part thereof adapted for non-rotative coöperation with one of said brackets, said last mentioned part being movable into and out 50 of engagement with a bracket by a lateral shifting movement of the swinging member relative to the brackets.

2. A stake pocket comprising bracket members adapted for attachment to a car, a 55

100

105

110

- swinging member having a portion formed to engage a stake and lateral portions lying in the axis of rotation of the swinging member and engaging said brackets to support
5 the swinging member thereon, a part of said lateral members being adapted for rotative coöperation with a bracket and a part adapted for non-rotative coöperation with a bracket, said swinging member being shift-
10 able on its axis of rotation to bring said parts of said lateral members selectively into engagement with a bracket.
3. A stake pocket comprising a swinging member having a part thereof formed to engage a stake and parts thereof forming lateral members disposed in the axis of ro-
15

tation of the swinging member, portions of said lateral members being round and a portion thereof being angular, and brackets adapted for attachment to a car and formed 20 with seats adapted to coöperate with the round and angular parts of the lateral members.

In testimony whereof we hereunto affix our signatures in the presence of two wit- 25 nesses, this 25th day of July, 1914.

ELMER DONADON.
MICHAEL M. MATHES.
